DESIGN FOR A COMBINED CAN HOLDER AND DISPENSER

Kenneth B. Van Woert, Sr., Los Altos, Calif.

Application September 5, 1939, Serial No. 87,053

Term of patent 7 years

To all whom it may concern:

Be it known that I, Kenneth B. Van Woert, Sr., a citizen of the United States and a resident of Los Altos, county of Santa Clara, State of California, have invented a new, original, and ornamental Design for a Combined Can Holder and Dispenser, of which the following is a specification, reference being had to the accompanying drawing, forming part thereof.

Figure 1 is a side elevational view of a combined can holder and dispenser, showing my new design.

Figure 2 is a front elevational view; and
Figure 3 is a top plan view thereof.

Figure 4 is a perspective view of the article, with the can holder portion separated from the dispenser portion.

I claim:

The ornamental design for a combined can holder and dispenser, substantially as shown.

KENNETH B. VAN WOERT, SR.
